UNITED STATES PATENT OFFICE.

STEPHAN BAADER, OF PHILADELPHIA, PENNSYLVANIA.

REVERSING-GEAR.

1,098,548.

Specification of Letters Patent. Patented June 2, 1914.

Application filed February 10, 1914. Serial No. 817,775.

To all whom it may concern:

Be it known that I, STEPHAN BAADER, a citizen of the United States, residing at Philadelphia, in the county of Philadelphia and State of Pennsylvania, have invented 5 certain new and useful Improvements in Reversing-Gears, of which the following is a specification.

My invention relates to improvements in 10 reversing gears, the object of the invention being to provide an improved fluid controlled mechanism for reversing the gear of a steam engine and more particularly to provide improved fluid controlled means for 15 locking the operating mechanism against movement, and releasing the same only at such times as the fluid controlled mechanism is in operation.

A further object is to improve upon the 20 construction covered in my prior application Serial No. 802,885, filed November 25, 1913.

With these and other objects in view, the invention consists in certain novel features of construction and combinations and 25 arrangements of parts as will be more fully hereinafter described and pointed out in the claims.

In the accompanying drawings: Figure 1 30 is a view in side elevation illustrating my improvements. Fig. 2 is a fragmentary view in section on an enlarged scale taken on the line 2—2 of Fig. 1. Fig. 3 is a similar view taken on the line 3—3 of Fig. 1, 35 and Fig. 4 is a fragmentary view in section on the line 4—4 of Fig. 2.

1 represents a cylinder which is closed at its ends by heads 2 and 3 respectively, the latter having a stuffing box 4 through 40 which an operating rod 5 projects. This rod is secured to a piston 6 within cylinder 1, and at its outer end is provided with an eye 7 for connection with a link (not shown) of any approved link motion to cause the 45 reverse of the engine as is commonly understood. This cylinder 1 will be located at any convenient point adjacent the link motion, and at a point removed from the engine cab and the movement of the piston 50 controlled by air or other fluid as will be hereinafter explained. A valve chest 8 is secured to the top of cylinder 1, and has a cylindrical valve chamber 9 in which a rotary valve 10 is mounted.

55 The cylinder 1 is provided at one side with a flat plate 15 which may be cast in-

tegral with the cylinder if desired, and on which at one end, a bracket 16 is fixed. This bracket 16 supports a rocker shaft 17 having a rocker arm 18 secured thereto and connected by a pivot 19 with a depending link 20. The lower end of the link 20 is connected by a pivot 21 with a lever 22, the pivot 21 being located approximately midway between the ends of the lever 22. 60 A rocking arm 23 is secured to the stem 24 of valve 10, and is connected at one end by a link 25 with one end of lever 22. The other end of lever 22 is connected by a pivot 26 with a depending block 27. This block 27 is provided on its inner face with a lug 28 which is guided vertically in a groove 29 in plate 15. The outer face of the block 27 is provided with a groove 30 in which a cam bar 31 is movable. This cam bar 31 65 at its forward end is secured to an arm 32 fixed to a split cross head 33 which clamps the operating rod 5 and a rod 34 together. The rod 34 projects through a split clamp 35 which is normally held in clamped position by means of a piston 36 located in a cylinder 37. 70

The cylinder 37 is located with its open end against one member of the clamp 35 and secured to the other member of the 75 clamp by bolts 38. The bolts 38 have heads 39 at one end and are projected through openings 40 and 41 in the clamp members and then screwed into ears 42 on the cylinder 37. The piston 36 fits the cylinder and 80 bears directly against a clamp member so that when air is admitted to the outer end of the cylinder, the piston and cylinder are moved in opposite directions to move the clamping members toward each other to 85 clamp the rod 34. When the pressure is released, the rod 34 can freely move. 90

A valve casing 45 is connected to the cylinder 37 by a pipe 43 adjacent its end, and is provided with a rotary valve 46 controlling the flow of fluid to the cylinder. This valve 46 has an inlet port 48 which normally registers with the inlet pipe 47, so that air under pressure is admitted to the cylinder to hold the rod 34 in clamped position. An exhaust port 49 is provided in valve 46, and an exhaust port 50 is provided in casing 45, so that when the valve 100 is permitted to turn a pre-determined distance, the air can freely escape in the atmosphere and permit the clamp to move to 105 released position. 110

The movement of valve 46 is controlled by the movement of the valve within casting 8 as set forth fully in my application above referred to, and hence need not be described herein in detail, except to say that the valves do operate in unison, so that when the rod 5 is to be moved, the rod 34 will be released, and when the rod 5 is to be held, the rod 34 will be securely clamped so that there can be no accidental movement.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a reversing gear, the combination with a longitudinally movable rod, a split clamp, a cylinder, bolts having heads on one end projected through openings in both members of the split clamp and secured to the cylinder, a piston within the cylinder bearing against one member of the split clamp, and means for admitting fluid to the cylinder between one end thereof and the piston, whereby the pressure of fluid within the cylinder operates to clamp the rod, substantially as described.

2. In a reversing gear, the combination with a cylinder, a piston in the cylinder, and an operating rod connected to the piston and projecting through one end of the cylinder, of a valve controlling the flow of fluid to and from the cylinder, means for moving the valve, a split clamp holding said rod against movement, a cylinder connected to one member of the split clamp, a piston in the last-mentioned cylinder engaging the other member of the split clamp, and means controlling the flow of fluid between the last-mentioned piston and the end of the last-mentioned cylinder, substantially as described.

3. In a reversing gear, the combination

with a cylinder, a piston in the cylinder, and an operating rod connected to the piston and projecting through one end of the cylinder, of a valve controlling the flow of fluid to and from the cylinder, means for moving the valve, a split clamp holding said rod against movement, a cylinder connected to one member of the split clamp, a piston in the last-mentioned cylinder engaging the other member of the split clamp, means controlling the flow of fluid between the last-mentioned piston and the end of the last-mentioned cylinder, said last-mentioned control operating simultaneously with the movement of the first-mentioned valve, substantially as described.

4. In a reversing gear, the combination with a cylinder, a piston in the cylinder, and an operating rod connected to the piston and projecting through one end of the cylinder, of a valve controlling the flow of fluid to and from the cylinder, manually operated means for moving the valve to open position, automatic means operated by the rod for returning the valve to closed position, means automatically operated for locking the rod against movement when said valve is closed, said last-mentioned means comprising a rod fixed to move with the operating rod, a clamp engaging the last-mentioned rod, and fluid controlled mechanism for operating the clamp, said last-mentioned mechanism comprising a cylinder, bolts projecting through one member of the spring clamp and secured to the cylinder, a piston in the last-mentioned cylinder bearing against the other member of the clamp, and said cylinder adapted to receive fluid between the end thereof and the piston, whereby the pressure of fluid moves the piston and cylinder in opposite directions, substantially as described.

In testimony whereof I have signed my name to this specification in the presence of two subscribing witnesses.

STEPHAN BAADER.
